United States Patent Office

Des. 183,433

Patented Aug. 26, 1958

183,433

DISPENSING CONTAINER

Paul S. Van Baarn, New York, N. Y.

Application March 11, 1957, Serial No. 45,172

Term of patent 14 years

(Cl. D58—26)

FIG. 1

FIG. 2

FIG. 3

Fig. 1 is a side view of the dispensing container, the other side of the container being identical with the side shown;

Fig. 2 is a top view of the same; and

Fig. 3 is a bottom view thereof.

The essential features of the design reside in the portions shown in full lines on the drawing.

I claim:

The ornamental design for a dispensing container, as shown and described.
